UNITED STATES PATENT OFFICE.

CLARENCE W. SEDGWICK, OF NEW YORK, N. Y.

DESIGN FOR A POCKET-CASE.

SPECIFICATION forming part of Design No. 23,443, dated July 10, 1891.

Application filed May 7, 1894. Serial No. 510,403. Term of patent 3½ years.

To all whom it may concern:

Be it known that I, CLARENCE W. SEDGWICK, a citizen of the United States, residing in the city of New York, county and State of New York, have invented and produced a new and original Design for a Pocket-Case, of which the following is a specification.

The accompanying drawings represent a pocket case embodying my design and consist of Figure 1, which is a perspective view of said case showing the ornamentation displayed upon it in relief, and Fig. 2, which is a cross section of said case with the design upon it.

15 The essential features of my design consist of a metal pocket case provided with a representation of a sloop-rigged vessel and a piece of water with waves upon the surface as shown in the accompanying drawings.

In Fig. 1, A is the pocket case; B is the 20 sloop-rigged vessel and C is the foreground of water.

The sloop B is represented with sails set riding upon the waves and presenting a full length view, while the water C forms the foreground of the picture.

In Fig. 2 E is the cover of the case upon which the ornamentation is displayed and D is the interior.

What I claim is—

25 The design for a pocket case substantially as herein shown and described.

CLARENCE W. SEDGWICK.
